UNITED STATES PATENT OFFICE

2,070,392

RECORDING AND REPRODUCING SYSTEM

John Bailey Browning, Camden, N. J.

Application July 1, 1931, Serial No. 548,143

9 Claims. (Cl. 274—46)

One object of this invention is to provide an improved method for recording the vibrations corresponding to sound and/or light impulses separately or simultaneously. Vibrations corresponding to sound and light impulses may be produced in the manner disclosed in Patent No. 1,770,205 to Goldsmith dated July 8, 1930 or in my prior application Serial No. 419,350 filed January 8, 1930.

Another object is to provide an improved pressing system or method of stamper production for vibrations corresponding to light and/or sound impulses. Reference is hereby made to "Recorded Programs" by A. J. Kendrick on pages 108, 109, 110 and 170 of the August, 1930 issue of Radio News, from which article it appears that a stamper is the negative record or die from which commercial records are duplicated.

Further objects as well as details of construction and operation will be hereinafter brought out in the following description and accompanying drawing, in which

Figure 1 is a plan view illustrating rather diagrammatically one embodiment of my process of recording.

Figure 2 is a side view showing the process of Figure 1.

Figure 3 is a cross-section taken along line 3—3 of Figure 2 and showing one form of recording tape prior to its being chased, ironed, chiseled or otherwise recorded upon. The thickness of the tape is greatly exaggerated.

Figure 4 is a cross-section taken along line 4—4 of Figure 2 and showing the recording tape at the moment it is being recorded upon.

Figure 5 illustrates cross-sections of two alternative forms of recording tape.

Figure 6 is a fragmental, diagrammatical illustration of a second embodiment of my new process.

Figure 7 is a cross-section taken along line 7—7 of Figure 6.

Figure 7a is a view showing a series of undulations being impressed in one edge of a tape (greatly exaggerated) by the drawing action of a stylus, which is shown in cross-section.

Figure 8 is a vertical cross-section through a stamper made by my process.

Figure 9 is a front view of one form of recording stylus.

Figure 10 is a cross-section taken on line 10—10 of Figure 9.

Figure 11 is a cross-section taken on line 11—11 of Figure 9.

Figure 12 is a side view of an alternative form of recording stylus.

Figure 13 is a side view of still another form of recording stylus.

The method of my invention consists broadly in chasing, chiseling, ironing, or otherwise forming undulations corresponding to sound and/or light impulses or vibrations upon one or both edges of a thin flexible band of malleable material such as metal. The metal tape after it is recorded upon may be wound upon a roll or spool and reproduced whenever desired by means of a suitable reproducing device as it is rewound upon another roll or spool. A preferable procedure is to wind the tape upon a suitable core to form a stamper, thus eliminating all the intermediate steps previously thought necessary in the recording art.

Referring to Figures 1 and 2 wherein is illustrated rather diagrammatically the embodiment of my invention wherein is recorded upon each edge of a metal tape a series of undulations corresponding to sound and/or light impulses, the tape 1 is shown being unwound from a roll or spool 2 and passed between forming rolls 3 and 4 to form the middle portion 5 and the thinner edge portions 6 and 7. The edge portions 6 and 7 are each chased, chiseled, ironed, or otherwise provided with a series of undulations 8 and 9 by means of the stylus 10 and 11 actuated by the diagrammatically illustrated electrodynamic recording devices 12 and 13. As clearly shown in Figure 2 each series of undulations is in a plane which is perpendicular to that of the metal tape. The elastic or rubber-covered roller 14 is shown supporting the tape as it passes through the recording devices. The recorded tape is then passed through a suitable apparatus 15 for setting the undulations in the metal and finally wound upon a roll or spool 16. The undulations in the tape may be set in the metal in a manner similar to that in which steel springs are hardened and tempered.

Figure 5 shows two possible alternative cross-sections of tapes that may be used in my process, the one indicated by 17 having tapered edges and the one indicated by 18 having rounded edges, instead of the thinned edges as illustrated in Figures 3 and 4.

Figures 6, 7 and 7a illustrate two alternative forms of my improved method. In both of these methods, the thinned edge of the tape as it is fed from one spool to the other is straddled by one or the other forked ends 25 or 26 of the stylus 20. In the first method the stylus is given a vertical

vibratory movement by means of a suitable electro-dynamic recorder of sound and/or light impulses and thus its forked end 25 produces the series of undulations 19 along the edge 6a of the 5 tape 1a. In the second of these methods, the stylus 20 has imparted thereto a vibratory movement perpendicular to the plane of the tape 1b and thus its end 26 produces the series of hill and dale undulations 19a in the edge 6b by a combined 10 twisting and drawing action. The requisite vibratory movement can be produced by means of a suitable form electro-dynamic recording device.

While only one edge is shown in Figures 6, 7 15 and 7a as being recorded upon, either process may well be applied to both edges of the tape. One edge of the tape may be provided with undulations corresponding to sound impulses and the other with undulations corresponding to light 20 impulses, or one or both edges may be impressed with undulations corresponding to both sound and light impulses, i. e. one series of undulations may represent a talking moving picture.

In the first embodiment of my invention, I may 25 use either of the styli shown in Figures 12 and 13. That of Figure 12 is formed with a pointed edge 21 at one end while that of Figure 13 is provided with a pointed end 22 and a button or ball end 23, either one of which may be used for recording. 30 As has been stated, the stylus 20 shown in Figures 9, 10 and 11 may be used in the second and third embodiments of my method. This stylus has two forked ends 25 and 26, the first of which is used when the undulations are produced in the edge of the tape by a vibratory movement of the stylus in the plane of the tape and the second of which is used when the stylus is vibrated perpendicular to the plane of the tape to produce a series of undulations by a twisting 35 and drawing action on the tape as it is fed 40 through the forked end.

The recorded tape made by any of the above described processes may be reproduced by passing it through a suitable reproducing device while 45 being rewound from one spool onto another. If the tape is to be reproduced in this manner, the step of forming the thinned edge portion shown in Figures 1 and 2 may be omitted. Duplicate records of this type may be made by passing the 50 recorded tape through a suitable pressing device in face-to-face contact with a second blank tape. This latter method of making duplicate records may be used to provide a sound track along the edge of a moving picture film.

55 My preferred method is to wind the recorded tape about the pin 27 and core 21a to form the stamper shown in Figure 8. The wound tape may be maintained in its spirally wound form in any suitable manner, as by means of a clamp- 60 ing ring 29. The thinned portions 6 and 7 thus form the walls of the grooves 28 of the stamper. In the finished record, the thinned portions 6 and 7 will form the grooves and the grooves 28 of the stamper will form the walls.

65 An alternative method of forming a stamper is to wind the tape 1 after it is provided with the thinned edge portions 6 and 7 into a blank and record thereupon by means of a suitable stylus mounted in a suitable recording device (not 70 shown).

Commercial records may be made in the usual ways known to the art from the stamper made in any of the previously described methods.

Thus it will be seen that I have provided a method for directly making the stamper of the recording process with the consequent elimination of the usual intermediate steps previously considered indispensable in the art. The disk stamper made by the method of Figures 1 to 4 results in a lateral-cut record while those of Figures 6 and 7 will produce one of the vertical-cut or "hill and dale" type, and that of Figure 7a will produce a "lateral"-cut record.

10 By my improved methods, I am enabled to produce a record of either the lateral-cut or "vertical-cut" type which can play for relatively long periods of time. In the case of the "vertical-cut" type, the grooves can be spaced as close as 15 five hundred (500) to the inch and the record made of sufficient diameter to play for as long as seven hours.

Since my records are capable of containing a large amount of program material, it is possible 20 to record several selections on each side.

The foregoing constitutes the essential and distinctive thought of my invention, but it is to be understood that the same may be combined with various other steps and details without 25 affecting the peculiar results obtained.

I claim:—

1. A method of recording which consists in chasing or engraving a continuous series of lateral undulations in the plane of the edge of a thin 30 tape corresponding to the impulses to be recorded.

2. A method of directly making a stamper which consists in producing an off-set edge in a thin strip of material, forming a continuous series of undulations in the off-set edge corresponding 35 to the impulses to be recorded, treating said strip to set the undulations and winding about a core.

3. A record consisting of a metallic strip, in the plane of whose edge is chased or engraved a continuous series of lateral undulations corre- 40 sponding to the impulses recorded.

4. A stamper for sound records consisting of a tempered strip of flexible metal provided along one or both edges with a series of undulations corresponding to the impulses recorded and 45 permanently wound into disk form, the windings being in direct contact.

5. A stamper blank for sound records consisting of a strip of malleable metal permanently wound into disk form, the windings being in direct contact.

6. A stamper blank for sound records consisting of a strip of malleable metal having a thinned edge portion permanently wound into disk form, said thinned edge serving to form a spiral groove 5 in said disk.

7. A method of recording on the edge of a moving picture film which consists in passing the unheated film through a pressing device in face-to-face contact with a metallic strip having im- 6 pressed therein undulations corresponding to the vibrations to be recorded.

8. A method of recording which consists in straddling a thin tape with a bifurcated recording tool and moving said tape as the tool is 6 vibrated in accordance with the impulses to be recorded.

9. A method of recording which consists in moving a thin tape with its edge in contact with a recording tool which is maintained in a plane perpendicular to that of the tape and vibrating said tool in accordance with the impulses to be recorded.

JOHN BAILEY BROWNING.
